UNITED STATES PATENT OFFICE.

STEPHEN C. LAFLIN, OF SOUTHBIDGE, MASSACHUSETTS, ASSIGNOR TO AMERICAN OPTICAL COMPANY, OF SOUTHBIDGE, MASSACHUSETTS, A CORPORATION OF MASSACHUSETTS.

BRIDGE FOR EYEGLASSES.

No. 897,468.

Specification of Letters Patent.

Patented Sept. 1, 1908.

Application filed May 6, 1907. Serial No. 371,962.

To all whom it may concern:

Be it known that I, STEPHEN C. LAFLIN, a citizen of the United States, and a resident of Southbridge, Worcester county, State of 5 Massachusetts, have invented certain new and useful Improvements in Bridges for Eye-glasses, of which the following is a specification.

My invention relates to bridges for eye-glasses and has for its object to provide a 10 strong and neat construction, particularly as regards the connection of the bridge with the straps which hold the lenses.

The invention is fully shown in the accompanying drawings, in which

Figure 1 is a front view of the completed bridge and straps; Fig. 2 is a perspective view of the bar out of which the bridge is formed by bending; Figs. 3 and 4 are an 20 end view and a front view respectively of the strap, before it is fastened to the bridge bar; Fig. 5 shows the bridge bar and straps put together, the straps being in section; Fig. 6 is a front view of the article with the 25 joints completed, but with the bar still straight; and Fig. 7 is a top view of the completed article, after the bending of the bridge.

The bar A out of which the bridge is 30 formed, is preferably made comparatively wide and thin at the center (see Figs. 2 and 5) swelling to greater thickness and at the same time contracting in width to a point A' at each side, and then having a beveled 35 or slanting face A² which together with the end lug A³ forms a recess. Each lug projects substantially at right angles to the adjacent portion of the bar A, and the thickness of material at the lug may be the same 40 as the thickness at the point A'; that is, the recess may be formed in the half-round end portion of the bar by two cuts, one to form the inner face of the lug A³, and the other to form the slanting face A².

The straps may be of any approved construction in their general features; thus 45 each strap is shown as made with a central member B, front and rear members B', B² between which the lens is received, and 50 curved arms B³ to fit the periphery of the lens C. One of the members B', B² has a screw threaded hole B⁴ for the end of the customary screw D which holds the lens in 55 the strap; the other member is shown with

a flaring hole B⁵ for receiving the counter-sunk head of the said screw. I desire it to be understood, however, that straps of other constructions may be employed.

In the central member B, at one side thereof, that is, adjacent to one of the members B', B², I provide a recess B⁶ and an opening B⁷ preferably of such dimensions that when the end of the bridge bar is inserted therein (with the lug A³ projecting inward through the opening B⁷, Fig. 5), the outer surface of said central member will be flush with the adjacent surface of the bridge bar A. The ends of the bridge bar having thus been inserted in the recesses and openings of the straps, the inner ends of the lugs A³ are upset or flattened to rivet or swage the straps to the bridge bar, as shown at the right-hand end of the bridge in Fig. 5, so as to obtain a smooth and neat finish. All that remains to be done after this is to solder the joints, swage the bridge bar at A' and A², and then to bend the bridge bar appropriately, for instance to the shape shown in Figs. 1 and 7. The joint of bridge bar and straps described above is very strong; the fact that the ends of the bridge 80 bar are flush with the front surface of the straps improves the appearance of the finished article.

I claim,

1. In combination with an eyeglass strap 85 provided with an opening in its central member and with a transverse recess located in the outer surface of said member and leading to said opening, a bridge bar the end portion of which is seated in said recess and provided with a lug within said opening.

2. In combination with an eyeglass strap 90 provided with an opening at one side of its central member and with a recess in its outer surface, leading to said opening, a bridge bar 95 the end portion of which is located in said recess flush with the outer surface of the strap and provided with a fastening lug within said opening.

3. In combination with an eyeglass strap 100 having a recess extending in the outer surface of its central member toward one of its end members and an opening with which said recess communicates, a bridge bar the end portion of which is located in said recess and 105 provided with a lug located within said opening and riveted or swaged against the inner surface of the strap.

4. In combination with an eyeglass-strap provided with a recess extending in the outer surface of its central member toward one of its end members, a bridge bar, the end portion of which is seated in said recess.
5. In combination with an eyeglass-strap whose central member is provided in its outer surface with a transverse recess extending to the edge of said member, a bridge bar, the

end portion of which is seated in said recess.

In testimony whereof, I have hereunto signed my name in the presence of two subscribing witnesses.

STEPHEN C. LAFLIN.
